PUMP

Ernest Wallace Aspden, Blackpool, England

Application February 24, 1937, Serial No. 127,537
In Great Britain March 7, 1936

1 Claim. (Cl. 103—161)

This invention relates to improvements in pumps particularly applicable for the hydraulic transmission of motor vehicles. According to the invention the pump comprises a plurality of 5 radial cylinders and pistons rotating around a central axis forming a master pump, gudgeon pins projecting from the pistons and connected to follow an eccentric path relatively to the cylinders to give the necessary stroke to the 10 pistons, a non-rotating casing capable of moving radially to the axis about which the cylinders rotate, a rotary casing, ball races between the rotary casing and the non-rotating casing upon which the rotary casing rolls, a guideway on 15 the rotary casing in which the ends of the gudgeon pins are located movement of the non-rotating casing varying the eccentricity of the guideway, an outer stationary casing, two diametrically opposite pistons connected to the non- 20 rotating casing, cylinders in the outer stationary casing in which the pistons are located, a port in each cylinder for the supply and release of fluid pressure to move the pistons therein and a stop on the non-rotating casing engaging a slot 25 in the outer stationary casing to prevent the diametrically opposite pistons from having more than a predetermined stroke.

The invention will be described with reference to the accompanying drawings in which:

30 Fig. 1 is a sectional elevation of the master pump.

Fig. 2 is a transverse section thereof.

Fig. 3 is a detail view of hollow shaft through which liquid is supplied from the master pump 35 to the pipe system to the wheel motors.

Fig. 4 is an outside elevation of part of the casing of the master pump.

The master pump D is a variable stroke oil pump and comprises a steel casting D¹ bolted to 40 the engine flywheel C and carrying three (or more) radial cylinders 1 in each of which is a piston 2 provided with gudgeon pins 3. The ends of the gudgeon pins 3 are located in guides 4^a in a casing 4, preferably of aluminium, and 45 the casing D¹, cylinders 1, pistons 2 and casing 4 all rotate around a stationary central shaft 9 within a stationary casing 5, ball races 4^b being provided between the rotating casing 4 and the stationary casing 5. The stationary casing 5 is arranged within an outer casing 10 bolted to the casing C¹ of the flywheel C and as formed 50 with a guide 11 adapted to slide in a slot 12 in the casing 10 to enable the eccentricity of the guides 4^a, in which the ends of the gudgeon pins 55 are located, to be varied relatively to the shaft 9

and the cylinders 1. The extent of the movement of the casing 5 is limited by the stop 6. In Figs. 1 and 2 the casing 5 is shown in the position in which the guides 4^a are concentric with the shaft 9 and consequently as the cylinders 1 and pistons 2 rotate about the shaft there will be no relative movement between the pistons and the cylinders.

Two cylinders 7 and 8 are formed in the casing 10 at diametrically opposite sides of the 10 sliding casing 5, operating as servo motors. In each of these cylinders a piston 13 is located and each piston is connected to the inner casing 4 by a rod 14. Each of the cylinders 7 and 8 is connected by a pipe 7^a and 8^a to a small pump H 15 through a slide valve H¹ controlled by a governor H². The pump H may be driven independently from the engine B as by an electric motor or it may be geared to the engine cam shaft b.

As hereinbefore stated the parts are shown in 20 Figs. 1 and 2 in position of no eccentricity of the pistons 2 (which is the position when the vehicle is stationary) in which position the cylinder 8 is in communication with the pipe 8^a and the piston 13 in the cylinder is at the inner end of 25 its stroke and the pipe 7^a is closed i. e. the apparatus is shown in the central or neutral position. The pipe 7^a is closed and the pipe 8^a to the cylinder 8 is open. Further, movement of the piston 13 in the cylinder 8 to move the casing 5 30 beyond its central position is prevented by the stop 6 and the guide 11 (Fig. 2) sliding in slots in the stationary casing 10 whereby the movement of the rotary casing 4 in one direction beyond its central position is prevented. 35

The engine speed for operating a valve to control the pipes 7^a and 8^a may be regulated by a spring and may be set at say 1000 revolutions per minute in cases where a quick get away is desired. 40

As the engine speed is increased above this predetermined minimum the valve moves to close the pipe 8^a and cuts off the supply of fluid to the cylinder 8 which allows the casing 4 to assume an eccentric position with respect to the 45 stationary casing 10 and the shaft 9 during which operation the casing 5 moves downwards with the pistons 13 and the guide 11 and stop 6 travelling in their slots. Further movement of the valve opens the pipe 7^a which supplies fluid 50 to the cylinder 7 and forces the piston 13 downwards until the guide 11 and stop 6 are at the reverse ends of their slots to that shown in Fig. 2. The rotary casing 4 and the guides 4^a for the gudgeon pin 3 will thus become more 55

centric to the cylinders 1 and as the cylinders rotate about the shaft 9 the gudgeon pins will be constrained to follow an eccentric path. This will give a stroke to the pistons 2 and cause them to draw in oil through the passage 15 which is connected to the pipe 9 from the reservoir G during their outward stroke when the port 16 in the passage 15 is uncovered by the bottom of the corresponding cylinder and discharge the oil under pressure through the passage 17 in the shaft 9 during their inward stroke when the port 18 in the passage 17 is uncovered by the bottom of the corresponding cylinder.

What I claim as my invention and desire to protect by Letters Patent is:

A pump comprising a plurality of radial cylinders and pistons rotating around a central axis forming a master pump, gudgeon pins projecting from the pistons and connected to follow an eccentric path relatively to the cylinders to

give the necessary stroke to the pistons, a non-rotating casing capable of moving radially to the axis about which the cylinders rotate, a rotary casing, ball races between the rotary casing and the non-rotating casing upon which the rotary casing rolls, a guideway on the rotary casing in which the ends of the gudgeon pins are located, movement of the non-rotating casing varying the eccentricity of the guideway, an outer stationary casing, two diametrically opposite pistons connected to the non-rotating casing, cylinders in the outer stationary casing in which the pistons are located, a port in each cylinder for the supply and release of fluid pressure to move the pistons therein and a stop on the non-rotating casing engaging a slot in the outer stationary casing to prevent the diametrically opposite pistons from having more than a predetermined stroke.
